UNITED STATES PATENT OFFICE.

WILLIAM HERBERT, OF SMITHFIELD, NORTH CAROLINA, ASSIGNOR OF ONE-HALF
TO LONDOLPH C. POWELL, OF SMITHFIELD, NORTH CAROLINA.

VEHICLE SPRING.

Application filed August 12, 1924. Serial No. 731,585.

To all whom it may concern:

Be it known that I, WILLIAM HERBERT, a citizen of the United States, residing at Smithfield, in the county of Johnston and State of North Carolina, have invented new and useful Improvements in Vehicle Springs, of which the following is a specification.

This invention relates to vehicle springs.

10 The object is to improve the construction of leaf springs for use especially in automobiles, by minimizing the jolting and jarring incident to rough travel and providing for absorbing the downward shock in the 15 several leaves of the spring when an inequality is encountered in the roadbed, and likewise to more slowly and delicately retard the rebound following such shock.

Another object is to provide a spring 20 having the above characteristics which may be constructed at a cost not exceeding the cost of an ordinary spring, which will be strong and durable, retaining its resiliency throughout the life thereof, and which may 25 be applied in position on the vehicle and retained therein without the use of bolts or clips to hold the several parts together, other than the necessary fastening means for holding the spring on the axle or frame, 30 the said spring giving that delicate cushioning effect obtained, generally, only with the aid of snubbers, shock absorbers, and like devices.

35 A full and complete understanding of the invention may be obtained from a consideration of the following detailed description, taken in connection with the accompanying drawing forming a part of this specification, it being understood that while the drawing 40 shows a practical form of the invention, the latter is not to be confined to strict conformity with the showing thereof, but may be changed or modified, so long as such 45 changes or modifications mark no material departure from the salient features of the invention, as specifically pointed out in the appended claims.

50 In the drawing, in which similar reference characters designate corresponding parts throughout the several figures:—

Figure 1 is a display view of the several leaves comprising the spring of the present invention and having the improvements incorporated therein;

Figure 2 is a side elevation of the assembled spring, in normal position; 55

Figure 3 is a similar view of one end thereof and drawn on an enlarged scale;

Figure 4 is a side elevation of the spring showing the position of the parts when 60 under maximum load;

Figure 5 is a bottom plan view of the same;

Figure 6 is a transverse sectional view, 65 taken on the line 6—6 of Figure 4 and drawn on a larger scale.

While the improvements constituting the present invention are illustrated in the accompanying drawing as applied to a well known form of semi-elliptical spring, it is 70 to be understood that the said improvements may be used with equal advantage on full elliptic springs, as the latter are, in effect, merely the duplication of the former placed in opposed relation to each other. 75

The leaves 1 of the spring are formed of the usual tempered, spring steel bands of different lengths, the same uniformly decreasing in length from the longest to the shortest, and being of any desired number 80 depending on the particular use to which the spring is to be put, the heavier the service the more leaves required and vice versa.

As in the drawing, the semi-elliptic spring shown is, in effect, the same as the lower 85 half of a full elliptic spring, and consequently the longest leaf is located at the top, while the shortest leaf is beneath the series 90 and is adapted to rest upon the automobile axle 2 or other support. Ordinarily these leaves are all initially formed on arcs of circles having different radii, that is to say, the inner or upper and longer leaf 1 is curved on the arc of a circle having a given 95 length of radius, such distance depending on the size, length and strength of the spring, all the other leaves being curved on successively increasing radii down to the shortest leaf so that, when in their normal state, they may be nested or interfitted, 100 when the longest and the shortest leaves, together with the intermediate leaves, will fit flat against each other in close contact throughout their opposite faces (Fig. 4).

One of the features of the present invention which is of primary importance is to initially form said leaves 1 all on the same radius, or in other words, the shortest 105

and intermediate leaves are exactly like a section of corresponding length cut out of the longest leaf, and the purpose of the displayed view, as shown in Figure 1 of the drawing, is to emphasize and to make clear such fact.

The upper and longer leaf 1 is provided with the usual terminal eyes 3 for the reception of shackle bolts 4 or other bolts for securing the spring directly to the frame member, and all of the leaves are of the same thickness and width throughout their lengths.

Each leaf, with the exception of the lowermost and shortest leaf 1, is provided adjacent to each end thereof with an abutment flange 5 secured in position, preferably by welding or brazing, and extending transversely thereof from edge to edge, each flange preferably having a base portion to strengthen the attachment of the same, and also having at its outer edge an overhanging lip or shelf 6 directed toward the center of the leaf, and adapted to overlap the free end 25 of the next shorter leaf beneath the same, when the parts are assembled.

In assembling the leaves, each succeeding shorter leaf may be sprung sufficiently to allow the ends to enter beneath the overlying lip 6, and when released, the said ends are in spaced relation to the abutments 5 and resting upon said lips, as shown in Figures 2 and 3 of the drawing. In order to prevent any lateral movement of the leaves relative 30 to each other, each leaf, with the exception of the shortest, bottom leaf, is provided with side arms 7 welded or otherwise connected to the side edges thereof, and extending down and across the side edges of the next shorter leaf and adjacent to the end thereof. Each side arm 7 is provided with an inwardly directed finger 8 formed integrally therewith and adapted to lie under the end of said next leaf, as clearly shown in Figure 6, 35 and to allow the same to freely slide between the same, as when the spring is subjected to different loads, or when encountering inequalities in the roadway.

When the leaves 1 of the spring are assembled, as above stated, with the ends thereof housed between the side arms and resting upon the lips or shelves 6, and before the spring is secured in position upon a vehicle, the like curvature of all the leaves 50 will produce a space between the same, as readily understood, said space gradually diminishing towards the ends which will contact with the next longer leaf above. When, however, the spring is secured in position, as by means of the ordinary clips 9, on the axle or other support 2, the leaves are necessarily clamped together at their centers, as shown in Figures 2 and 3, and the space 60 is then equally divided at either side of the clamping members, the points of contact

still remaining at the ends of the several leaves, the ends being spaced, as before stated, from the co-acting abutments.

The full, inherent resiliency of each leaf of the spring is thus preserved, there being no bolt holes through the leaves to weaken the same, nor bolts traversing them to cause the same to bind and to increase friction. As the spring is straightened out under the strain of a maximum load, as shown in Figure 4, the ends of the leaves contact with the abutments, and gradually bring the resistance of the spring to the load into effect to relieve the shocks of jolting and jarring. The advantage of having all of the leaves initially formed on the same curve, lies in the fact that it overcomes the overstrain on the short leaves, and the said leaves are caused to function in unison to render the same more flexible under load and more rigid on the rebound.

What is claimed is:—

1. A vehicle spring comprising a plurality of curved leaves each of which is initially formed on the same radius, said leaves being successively shorter in length, and means for slidably engaging and holding the ends of the leaves together.

2. A vehicle spring comprising a plurality of curved leaves of successively shorter lengths, each shorter leaf being located against the convex side of the adjacent longer leaf and having the same normal curvature when initially formed.

3. A vehicle spring comprising a plurality of successively shorter curved leaves, each leaf, except the shortest leaf, having near each end and on the convex side thereof, a fixed transverse abutment normally spaced from the ends of the next succeeding shorter leaf when the spring is not under load, and provided with an overhanging lip.

4. A vehicle spring comprising a plurality of successively shorter leaves having the same initial curvature to produce, when nested, spaces diminishing from the center outwardly to the contacting ends, means for slidably connecting the ends to the next longer leaf, and means for clamping the central portions thereof to an axle or support to cause the said separating space to be at each side of the support with the ends of each leaf in contact with the next longer leaf.

5. A vehicle spring comprising a plurality of successively shorter spring leaves, clamping means for securing the leaves together at the center with the ends of the leaves contacting with the next adjacent longer leaf, and transverse overhanging flanges formed on each leaf, except the shortest leaf, to form abutments for the ends of the next shorter leaf when the spring is under extreme load.

6. A vehicle spring comprising a plurality of successively shorter spring leaves, clamp-

ing means for securing the leaves together at the center with the ends of the leaves contacting with the next adjacent longer leaf, and transverse overhanging flanges formed 5 on each leaf, except the shortest leaf, to form abutments for the ends of the next shorter leaf when the spring is under extreme load, the lip of said flange receiving the end of said shorter leaf to hold the same 10 in contact and to permit sliding movement of the ends of the leaves.

7. A vehicle spring comprising a plurality of successively shorter leaves, each leaf, except the shortest leaf, having fixed trans- 15 verse abutments in spaced relation to the ends of the next shorter leaf and adapted to contact with said ends only when the spring is under maximum load, an extended lip on each abutment to overlie the said ends at 20 all times, and depending side arms carried by each leaf, except the shortest leaf, and adapted to engage the side edges of the next

shorter leaf and near the end thereof to prevent any relative lateral movement thereof, said side arms having inwardly directed, terminal fingers bearing upon the outer face 25 of the next shorter leaf.

8. A vehicle spring comprising a plurality of successively shorter leaves, each leaf, except the shortest leaf, having fixed transverse 30 abutments in spaced relation to the ends of the next shorter leaf and adapted to contact with said ends only when the spring is under maximum load, an extended lip on each 35 abutment to overlie the said ends at all times, and depending side arms carried by each leaf, except the shortest leaf, and adapted to engage the side edges of the next shorter leaf and near the end thereof to prevent any relative lateral movement 40 thereof.

In testimony that I claim the foregoing as my own, I have hereto affixed my signature.

WILLIAM HERBERT.
